UNITED STATES PATENT OFFICE.

ADOLPH HELLENBERG, OF NEW YORK, N. Y.

DESIGN FOR A NECKTIE.

SPECIFICATION forming part of Design No. 18,903, dated February 5, 1889.

Application filed December 22, 1888. Serial No. 294,426. Term of patent 3½ years.

To all whom it may concern:

Be it known that I, ADOLPH HELLENBERG, of the city, county, and State of New York, have invented and produced a new and original Design for a Necktie, of which the following is a specification.

My newly-designed necktie is fully illustrated in the accompanying drawing, to which reference is made.

- 10 The head A of the necktie exhibits the straight top line, a, straight side line, b, opposite diagonal line c, and straight bottom line, d. Depending from the bottom of the head are two skirts or aprons, B B', each showing a straight line, e e', and one showing an opposite line, f, curved at f' to meet the diagonal line c and straight bottom line, d. At the top of the head, and parallel with the straight top line, a, is a straight line of orna-

mentation, C, reaching from line c to line b. 20 This ornamentation comprises spaced leaves or dots i i and a connecting undulating line, i. Parallel with the edge e' of the skirt or apron B' is a line, D, of ornamentation at right angles to the line of ornamentation C, one being spaced from the other by the head A. This line D of ornamentation exhibits the spaced leaves or dots j and a broken line, j'.

I claim—

25 The design for a necktie herein shown and described, the same consisting of the straight lines a b d, diagonal line c, and line C of ornamentation parallel with the top line, a, showing spaced dots and leaves.

ADOLPH HELLENBERG.
